UNITED STATES PATENT OFFICE.

MORRIS SHAPIRO, OF NEW YORK, N. Y.

DESIGN FOR A PLAQUE OR PANEL.

56,387.

Specification for Design.

Patented Oct. 5, 1920.

Application filed April 22, 1920. Serial No. 375,903. Term of patent 7 years.

To all whom it may concern:

Be it known that I, MORRIS SHAPIRO, a citizen of the United States, residing at New York, borough of the Bronx, in the county of Bronx and State of New York, have invented a new, original, and ornamental Design for a Plaque or Panel, of which the following is a specification, reference being had to the accompanying drawing, forming part thereof.

In the drawings, the figure represents a plan view of my design, as applied to a plaque or panel.

The said design is printed, painted, molded, cast, carved, engraved, stamped or otherwise marked upon a plaque or panel constructed of wood, paper, glass, horn, bone or ivory, and said plaques or panels bearing said design may be combined with other plaques bearing a similar design to provide a border if desired.

I claim:

The ornamental design for a plaque or panel substantially as shown and described.

MORRIS SHAPIRO.
